UNITED STATES PATENT OFFICE

JOHN HANSEN, OF BETTENDORF, IOWA

POWER BALING MACHINE

Application filed May 4, 1928. Serial No. 275,225.

My invention has reference to power baling machines, and pertains more specially to that class of such machines in which the ram, or platen which is employed for compressing the load of paper or other material in the machine is given a vertical movement upwardly or downwardly by means of a pair of screw-threaded shafts at the ends of the machine, and nuts or travellers operating thereon and carrying the platen devices. In these machines it is designed to have the material introduced through the top, and it has therefore been found to be necessary to remove the platen temporarily from its position above the load. A common manner of doing this has been to mount the platen in such a manner that it could tip to one side or the other after being free of the machine, at a point above the same. In the earlier art the platen was left to fall by the force of gravity to one side or the other, but in more modern machines, especially those of a larger build, in which the material is frequently fed into the machines from a floor above the one on which the machine is installed, it is frequently desired to feed the material in from one side of the machine, and have the platen move in the opposite direction.

The chief purpose of the present invention is to provide a trip for the platen devices, which will operate when the platen has reached a desired point above the box, and which will initiate a tilting movement of the platen in the desired direction. In connection therewith a slidable support for the platen is provided, permitting an easy movement of the platen outwardly and the reverse. In addition thereto means is provided for preventing the platen from being forcibly drawn or tipped in the opposite direction, as might occur from the same becoming entangled with fabrics or cords which are included in the material with which the machine is being supplied.

The parts of the machine which embody the invention are of a simple and efficient character, and aid in decreasing the cost of production of the machine itself.

The particular construction, arrangement, and operation of the invention will be more

fully set forth in the following specification, taken in connection with the accompanying drawings, in which;

Fig. 1 is an end view of a machine equipped with the invention, with a part of the screw 55 8 broken away.

Fig. 2 is a plan view, with the upper bearings for the shafts 8 omitted.

Fig. 3 is a detail of the platen tripping mechanism. 60

The reference number 1 indicates a base, mounted upon which are end frames 2, having upper cross-braces 3. Said frames are united by longitudinal pieces 4, all of the frames and cross-pieces being preferably of a channel-plate formation. On the base 1 is also supported a receptacle for the material to be baled, the ends of which are formed of pairs of plates 5 and 6, each pair of which is separated by a vertical channel 7. The sides of the receptacle are of a common hinged door construction, which are not shown in the drawings, and which are positioned just beneath the pieces 4. At the ends of the machine are rotatably mounted vertical shafts 8, each screw-threaded throughout the greater part of its length, and each adapted for operation by a gear-wheel 9 on the lower end thereof, only one of said wheels 75 being shown. Said gear-wheels are adapted to be simultaneously rotated from a drive mechanism common to both. 80

Each of said shafts 8 is provided with a nut or traveller 10, upon which are pivoted yokes 11, each provided with a short shaft 85 upon which is rockingly mounted a bearing 13, said bearings being united by and supporting a platen-frame 14, of arch formation. The upper bar 14^a of the frame 14 is substantially horizontal, and the ends thereof 90 are movable vertically in the channels 7 in the ends of the receptacle. Secured to the lower side of said bar are plates 15, supporting a series of plates 16 which form the platen. Said plates are preferably of a channel formation, with the flanges thereof turned upwardly. 95

At the edges of the channels 7, on the outer faces of the plates 5 and 6, are angle-plates 17 and 18, the latter of which are projected 100

upwardly and outwardly above the top of the receptacle, forming arcuate tracks 19, which permit a movement of the platen-frame and platen carried thereby toward that side of the machine, and tipping the platen into a plane at an angle with that of its working position, as shown in broken lines in Fig. 1. This opens the top of the machine so as to permit of the feeding of material into the receptacle from the side opposite to that toward which the platen is moved. The angle-plate 17 is extended upwardly to a sufficient height to interfere with a movement of the platen-frame toward that side of the machine from which the material is fed.

In the upper part of the machine, at the ends thereof, are reinforcing plates 20 and 21, uniting the end plates of the receptacle and the end frames of the machine, and secured to one of the bearings 13 is a frame 22, from which projects a trip 23, in a position to strike against the lower edge of the plate 20 when the platen has reached a desired position in the upper part of the machine, as shown in Fig. 3. This tends to arrest the movement of the trip, and as the traveller 10 continues to move upwardly the trip 23 is tipped into a position to pass the obstruction, as shown in Fig. 3. This operates to rock the bearing 13 slightly, at the same time tipping the platen frame until the bar thereof rests against the track 19, as shown in said figure. A continued movement of the screws 8 carries the platen-frame and platen outwardly along the tracks in the manner hereinbefore mentioned. On a reverse movement of the screws the platen-frame is again moved inwardly, sliding upon said tracks, and bringing the platen into position for a compressing operation. In the outward movement of the platen the bearing 13 continues to rotate, causing a complete clearance between the trip 23 and plate 20, the only engagement between such parts being the contact of the trip with the lower edge of the plate. In the return movement of the platen the end of the trip swings in below the plate again. As a matter of fact the plate 20 is made use of on account of providing a convenient interference for the movement of the trip, and any kind of a stop or obstacle which will give the desired movement to the trip can be substituted therefor.

The amount of movement to be given to the platen-frame for the purpose of upsetting the same is only such as is necessary to overbalance the same, or rock the same from a possible neutral support, the subsequent movement of the frame outwardly being produced by the weight of the platen-frame and platen, or by gravity.

Both of the bearings 13 can be provided with the trip mechanism, if desired, but this is found to be unnecessary. It will also be noted that the invention is not limited in its

use to machines of the screw operated type, but that it can be adapted for use with any mechanism which includes vertically movable parts or elements at the ends of the machine, upon which the platen frame can be 70

rockingly mounted.

What I claim, and desire to secure by Letters Patent, is:

1. A device of the class described, comprising a receptacle, provided with vertical 75 channels in its ends, a platen and frame therefor movable in said channels, outwardly diverging tracks forming extensions for the edges of said channels, at one side thereof, operating mechanism for said platen including vertically movable parts with which the platen frame is rockingly connected, a trip 80 on one of the connections and movable therewith, a detent in the line of travel of said trip, and frame extensions for preventing a 85 movement of the platen frame toward that side of the machine opposite to said tracks.

2. In a power baling machine, a receptacle, a platen movable therein and provided with supports rockingly mounted, means for holding 90 said supports with the platen in operative position throughout its movement in the receptacle and above the same, divergent tracks in the upper part of the machine, a trip device movable with one of the supports at its rock- 95 ing point, and stationary means cooperating therewith for checking the movement of said trip, and causing said supports and platen to overbalance in the direction of said tracks.

3. In a power baling machine, a receptacle 100 provided in its ends with vertical channels, the edges of which serve as guides, the edges at one side thereof being carried straight upwardly to a point above the receptacle, and the opposite edges being projected into outwardly diverging tracks also above said receptacle, a platen and supporting frame therefor movable in said channels, mechanism at the ends of said receptacle for the operation of said platen, including vertically 105 movable elements with which the platen frame is rockingly connected, one of said connections being provided with a trip device, and means in the line of travel of said trip device to engage therewith and cause the 110 platen frame and platen to overbalance in the direction of said tracks.

In testimony whereof I affix my signature,
JOHN HANSEN.
